Des. 227,111
Patented June 5, 1973

227,111

HOUSING FOR AN ELECTRONIC TEST SCORING MACHINE

Perry Hall Rosen and Roy E. Seymour, Beaverton, and
Walter James Sirois, Sherwood, Oreg., assignors to
Automata Corporation, Richland, Wash.

Filed June 4, 1971, Ser. No. 150,261

Term of patent 14 years

Int. Cl. D10—05

U.S. Cl. D25—1 R

FIG. 1

FIG. 2

FIG. 3

FIG. 4

FIG. 5

FIG. 6

FIG. 1 is a front perspective view of a housing for an electronic test scoring machine showing our new design; FIG. 2 is a front elevational view thereof;

FIG. 3 is a left side elevational view thereof, the right side being substantially a mirror image thereof;

FIG. 4 is a rear elevational view thereof;

FIG. 5 is a top plan view thereof, and

FIG. 6 is a bottom plan view thereof.

We claim:

The ornamental design for a housing for an electronic test scoring machine, as shown and described.
